UNITED STATES PATENT OFFICE.

THOMAS KELLY, OF CHICAGO, ILLINOIS.

DESIGN FOR A LAVATORY.

SPECIFICATION forming part of Design No. 37,270, dated December 20, 1904.

Application filed November 10, 1904. Serial No. 232,254. Term of patent 14 years.

To all whom it may concern:

Be it known that I, THOMAS KELLY, a citizen of the United States, residing at Chicago, in the county of Cook and State of Illinois, have 5 invented a new, original, and ornamental Design for a Lavatory, of which the following is a specification, reference being had to the accompanying drawing, which shows a perspective view of a lavatory embodying my new design.

What I regard as new, and desire to secure by Letters Patent, is—

The ornamental design for a lavatory, as herein shown.

THOMAS KELLY.
